UNITED STATES PATENT OFFICE.

EMANUEL L. RICHARDS, OF NEW LONDON, CONNECTICUT.

GRANULATING-MACHINE.

No. 823,550.

Specification of Letters Patent.

Patented June 19, 1906.

Application filed February 5, 1906. Serial No. 299,481.

To all whom it may concern:

Be it known that I, EMANUEL L. RICHARDS, a citizen of the United States, residing at the city of New London, in the county of New London and State of Connecticut, have invented certain new and useful Improvements in Granulating-Machines, of which the following is a specification.

My invention has relation to a machine for granulating plastic or semiplastic materials, especially such as pharmaceutical preparations, and in such connection it relates particularly to means for dividing the materials into granules of uniform size.

Heretofore the machines employed for granulating pharmaceutical preparations produced granules of unequal size, and consequently of varying weight. Such granules when the preparations were formed into tablets, pastils, or the like by special machinery increased or decreased the weight of the same. It is well known, however, that an increase of weight of a tablet containing poisonous matter is dangerous, thereby jeopardizing life, while a decrease in weight of a tablet fails to produce desired effects.

The principal objects of my invention are, first, to overcome the above-described disadvantages of granulating-machines; second, to provide such a machine with revolving means and a rotating disk with slots of equal length through which the material is forced by the revolving means for a predetermined period of time to produce granules of uniform size and length and of equally corresponding weight; third, to so bend portions of the metal of a disk intermediate of the slots therein as to form raised cutting edges adapted to readily sever the material prior to passage through said slots; fourth, to provide such a machine with an adjustable receiving-receptacle for material to be granulated to hold the same and the revolving means arranged therein in varying positions with respect to the slotted disk of the machine; fifth, to provide such a machine with a rotating support for the disk thereof adapted to permit of ready removal and replacing of said disk and also for retaining material adapted to pass from the receiving-receptacle thereof, and, sixth, to provide such a machine with a receiving-hopper adapted to conduct granulated material into any suitable receiving vessel or to retain the same in the absence of such a vessel.

The nature, characteristic features, and scope of my present invention will be more fully understood from the following description, taken in connection with the accompanying drawings, forming part hereof, in which—

Figure 1 is a view illustrating, partly in elevation and partly in section, the granulating-machine, the means for adjustably supporting the receiving-receptacle, the support for the slotted disk, and the mechanism for rotating and carrying the support and receiving-hopper, and means for closing the outlet-opening thereof, all embodying main features of my said invention. Fig. 2 is a top or plan view, partly in section, of the machine of Fig. 1. Fig. 3 is a vertical sectional view, enlarged, on the line *xx* of Fig. 2. Fig. 4 is a detail view, enlarged, illustrating in section the receiving-receptacle for the material to be granulated, a portion of the slotted disk and its support arranged beneath the same and revolving arms for forcing material through slots of the disk; and Fig. 5 is a vertical sectional view, enlarged, on the line *yy* of Fig. 2.

Referring to the drawings, *a* represents a base to which are suitably secured standards *a'* and *a''*, serving to hold an annular body or support *b*, connected therewith by bolts *a³*, a certain distance above the base *a*, as shown in Fig. 1. The support *b* is provided with bosses *b'*, preferably formed integral therewith, to which by means of brackets *b²* and bolts *b³* and *b⁴* are secured flanged rollers *b⁵*.

As shown in Figs. 1 and 3, the rollers *b⁵* serve to rotatably support an annulus or ring *c*, and by means of the flanges *b⁶*, engaging the interior surface of the contracted portion *c'* of the ring, serve also to hold the same securely in position on the rollers *b⁵* and to prevent any sidewise displacement of the ring *c* with respect to the support *b*. In the interior portion thereof the ring *c* is provided with teeth *c²*, meshing with a gear-wheel *d*, supported by a shaft *d'*, arranged in the standard *a'*. To the shaft *d* are secured fixed and loose pulleys *d²* and *d³*, which by means of a belt *d⁴* (indicated by dotted lines in Fig. 1) are driven from any suitable source of power. (Not shown.) The belt *d⁴* is actuated, preferably, by a belt-shifter *e*, slidably arranged on rods *a⁴* of the standard *a'*, which by means of links *e'* is connected with

a weighted arm e^2 , carried by a rod e^3 , movably arranged in the standard a' , as shown in Figs. 1 and 2. The rod e^3 by its bent portion e^4 permits of the actuation of the belt-shifter e , which is held in the position given by the weight e^5 of the arm e^2 . The shaft d' when rotated by the fixed pulley d^2 imparts to the ring c by means of the gear-wheel d a rotary movement for a purpose to be presently fully described. To prevent any lifting of the ring c from the rollers b^5 by the gear-wheel d , the brackets b^2 of the annular support b , arranged adjacent to the gear-wheel d , are provided with additional guide-rollers b^8 , engaging the upper surface of the ring c , and thus holding the same in position on the rollers b^5 , as will be readily understood in Fig. 5. However, projections b^9 and b^{10} , formed integral with the brackets b^2 , will support and also prevent the lifting of the ring c in case the rollers b^4 and b^8 fail to serve their purpose. The ring c serves to support an annular grate-like body f , which in turn supports a disk g , provided with slots g' , preferably arranged radially with respect to the central vertical axis of the disk. Both the grate-like body f and disk g are held in position in the ring c by an annulus h , connected therewith by means of bolts h' , which, in conjunction with the disk g , forms a shallow receptacle for material to be granulated, the material having passed from a receptacle i , containing the same. The receptacle i is held in proximity to the disk g by a shaft k and extensions i^2 of the lower section i' of the receptacle i , which by resting on the standard a^2 support the receptacle at one side thereof, while the receptacle at the side opposite to the extensions i^2 is supported by the shaft k , as shown in Fig. 1. The shaft k at its free end is supported by a bracket k' , pivotally connected in the point k^2 to the standard a' , while its other end by means of bearings i^3 , formed integral with the receptacle i and its lower section i' , is supported by the same. Between the extensions i^2 of the receptacle i and the standard a^2 are placed washers l , which, as shown in Figs. 3 and 4, hold the receptacle i with its outlet-opening i^4 in proximity to the disk g and when replaced by washers of greater or less diameter than those shown will permit the receptacle i to touch with its lower surface i^5 the disk g or be held more or less above the same. These different positions of the receptacle i with respect to the disk g are necessary to prevent discharge or removal of material from the receptacle by the disk g , moving with its outer portion beneath the outlet-opening i^4 and lower surface i^5 thereof. Loose material or such as is of less consistency, for instance, will require the lowering of the receptacle close to the disk g , while dough-like material or such of greater consistency will per-

mit of a slight raising of the same above the disk, as such material will not readily pass between the lower surface i^5 thereof and the disk g . The shaft k , partially supporting the receptacle i , is rotated by a gear-wheel m actuated by a gear-wheel m' , secured to the positively-driven shaft d' .

As shown in Figs. 2 and 4, within the receptacle i are arranged pressure-arms o and o' , preferably formed integral with each other, which by being secured to the shaft k are rotated by the same in a direction opposite to that of the disk g . These arms are of a substantially S shape in cross-section, and the outer surface of the lower curved end portions o^2 thereof are held in alinement with the lower surface i^5 of the receptacle i . The material to be granulated and placed in the receptacle i is forced by the revolving arms o and o' through its outlet i^4 toward and against the disk g , which in the portions between the slots g' is bent to form cutting edges g^2 , projecting above the disk g , as shown in Fig. 4. These cutting edges g^2 cut the material prior to the forcing of the same through the slots g' of the disk g by the curved portions o^2 of the arms o and o' , which cutting thereof is facilitated by the oblique position of the bent portions g^3 of the disk g , traveling with the raised cutting edges g^2 thereof in a direction opposite to that of the rotation of the arms o and o' . The slots g' of the disk g being of a predetermined length and equal size and the speed of rotation of the arms o and o' being of a fixed ratio with respect to the speed of travel of the disk g insure the formation of granules of uniform size and length, which granules when compressed will form tablets, pills, or pastilles of equal weight and thickness. The bars f' of the grate-like body f , supporting the disk g , are provided at their upper bearing-surfaces with slanting portions f^2 , so as to offer no resting-place for accumulation of granulated material and taper toward their lower portions to facilitate exit of granulated material therethrough. The disk g in its rotation will conduct a certain portion of the material from the receptacle i by forcing the same outward between the lower end i^5 of the receptacle i at the left-hand side of Fig. 4. This portion of the material leaving the receptacle i is, however, retained on the disk g by the annulus h , forming, in conjunction therewith, a shallow receptacle until by the rotation of the disk g it is conducted back into the receptacle by contacting with the curved edge i^6 at the right-hand side of Fig. 4, which curved edge i^6 facilitates its entrance into the same between the lower portion i^5 of the receptacle and the disk g , as will be readily understood from Figs. 1 and 4. The material granulated by the arms o and o' and disk g drops directly into a receiving vessel r , arranged below the

disk-support *f* and carried by the receptacle-support *b*, as shown in Fig. 3. This vessel may conduct the granulated material into any vessel placed beneath the same or may retain the material, for which purpose the receptacle is provided with a slide *t*, closing or freeing the outlet-opening *r* thereof.

Having thus described the nature and objects of my invention, what I claim as new, and desire to secure by Letters Patent, is—

1. In a machine of the character described, a receptacle for material to be granulated, a rotatable slotted disk traveling beneath said receptacle, a shaft mounted in said receptacle and carrying arms having successive portions for forcing the material to and through said disk.

2. In a machine of the character described, a receptacle for material to be granulated, a disk having openings rotating beneath said receptacle, and means arranged parallel to said disk and adapted to be brought successively into proximity to said disk to force the material to be granulated to and through the slots of said disk.

3. In a machine of the character described, a receptacle for material to be granulated, a slotted disk traveling beneath said receptacle, oblong means arranged in said receptacle parallel to said disk, and adapted to be brought successively into the path of the traveling disk to force the material to be granulated to and through the slots of said disk.

35 4. In a machine of the character described, a receptacle for material to be granulated, a slotted disk rotating beneath said receptacle, a shaft mounted in said receptacle and carrying a device provided with oppositely curved portions adapted to be successively brought into the path of travel of said disk to force the material to be granulated to and through the slots of said disk.

5. In a machine of the character described, 45 a receptacle for material to be granulated, a disk having slots and raised portions forming cutting edges traveling beneath said receptacle, a shaft mounted in said receptacle parallel to said disk and carrying a device having portions oppositely conforming in shape to each other to force successively the material to be granulated to said disk and for cutting said material prior to its passage through the slots thereof.

55 6. In a machine of the character described, a receptacle for material to be granulated, a slotted disk having bent portions forming cutting edges, means for holding said disk beneath said receptacle and rotating in one direction a shaft mounted in said receptacle and carrying arms having portions oppositely conforming in shape to each other and revolving in said receptacle in a direction opposite to that of the said disk, said arms

arranged to successively force said material to 65 be granulated to and through the slots of said disk, and the cutting edges of said disk so arranged as to facilitate the granulation of said material prior to its passage through the slots of said rotatable disk.

7. In a machine of the character described, a receptacle for material to be granulated, a slotted disk, means for supporting and rotating said disk beneath said receptacle, a shaft mounted in said receptacle parallel to 75 said disk and carrying arms having end portions oppositely conforming in shape to each other to successively force material to be granulated to and through the slots of said disk and means for supporting said receptacle 80 in variable positions with respect to said rotatable disk.

8. In a machine of the character described, a receptacle for material to be granulated, a slotted disk, means for supporting and rotating said disk beneath said receptacle, a shaft mounted in said receptacle and carrying revolving arms for successively forcing the material to be granulated to and through the slots of said disk, means for holding said 90 receptacle in variable positions with respect to said disk and means for receiving and supporting the granulated material and having an outlet-opening provided with a slide for removably closing the same.

9. In a machine of the character described, a receptacle for material to be granulated, a disk having slots, means for supporting and rotating said disk beneath said receptacle, said means arranged to retain the material 100 leaving said receptacle, and said disk in conjunction with said means arranged to conduct the material back to said receptacle.

10. In a machine of the character described, a receptacle for material to be granulated, a disk having slots rotating beneath said receptacle, and arms having curved ends revolving in said receptacle the curved ends of said arms arranged to be successively moved over said disk to force the material into engagement therewith and through the slots thereof.

11. In a machine of the character described, a receptacle for material to be granulated, a disk having slots or openings arranged beneath the outlet-opening thereof, a support for said disk, means having rolls for holding and maintaining said support in proper position with respect to said receptacle, and means for engaging said support and for 115 moving the same over said rolls.

12. In a machine of the character described, a receptacle for material to be granulated, a disk having slots or openings for partially closing the outlet thereof, a holder for said 125 disk, comprising a ring, a grated body arranged in the ring supporting said disk, and an annulus for removably holding said

grated body and disk in position in said ring.

13. In a machine of the character described, a receptacle for material to be granulated, a disk having slots or openings for partially closing the outlet thereof, a holder for said disk, comprising a ring, a grated body arranged in the ring supporting said disk, an annulus for removably holding the grated body and disk in position in said ring, and a holder for the ring having rolls for supporting said ring, and means for engaging said ring and revolving the same on said rolls.

14. In a machine of the character described, a receptacle for material to be granulated, a disk having slots or openings for partially closing the outlet thereof, a ring for the disk having teeth, a support for the ring having rolls upon which said ring is placed, means for engaging the teeth of said ring and moving the same over said rolls, a receptacle for material passing through the slots of the disk and carried by said support, said receptacle having means for closing the outlet thereof.

15. In a machine of the character described, a standard, a receptacle for material to be granulated engaging said standard, a shaft supported by the standard and receptacle, a disk having slots arranged below the receptacle in said standard, and means carried

by said standard for engaging said receptacle and arranged to hold the same in varying positions with respect to said disk.

16. In a machine of the character described, a standard, a positively-driven shaft, a receptacle for material to be granulated engaging said standard, a second shaft pivotally supported at one end by said standard and at the other end by said receptacle, said second shaft arranged to assist in the support of said receptacle, a disk having slots, a holder for said disk rotatably arranged in said standard having teeth, arms secured to said second shaft and arranged in said receptacle, said arms adapted when rotated to force the material against said disk and through the slots thereof, and a gear mechanism arranged to transmit the movement of the positively-driven shaft to the second shaft and the arms thereof and to said holder by engaging the teeth thereof.

In witness whereof I have hereunto set my signature in the presence of two subscribing witnesses.
